UNITED STATES PATENT OFFICE.

FRANK L. FUHR, OF UHRICHSVILLE, OHIO.

DESIGN FOR A DISPLAY-BOARD.

41,727.

Specification for Design.

Patented Aug. 29, 1911.

Application filed April 21, 1911. Serial No. 622,635. Term of patent 14 years.

To all whom it may concern:

Be it known that I, FRANK L. FUHR, a citizen of the United States, residing at Uhrichsville, in the county of Tuscarawas and State of Ohio, have invented a certain new, original, and ornamental Design for a Display-Board, of which the following is a specification, reference being had to the accompanying drawing, forming a part thereof.

The figure is a perspective view of a display board, illustrating my new design.

I claim:

The ornamental design for a display board, as shown.

FRANK L. FUHR.

Witnesses:

A. W. ELSON,
HAROLD J. ELSON.
